UNITED STATES PATENT OFFICE.

JOSEPH F. SCHAEFER, OF CLEVELAND, OHIO, ASSIGNOR TO THE VAN DORN IRON WORKS COMPANY, OF CLEVELAND, OHIO, A CORPORATION OF OHIO.

EXTENSION-DRAWER CONSTRUCTION.

1,160,455.

Specification of Letters Patent.

Patented Nov. 16, 1915.

Application filed April 2, 1914. Serial No. 828,989.

To all whom it may concern:

Be it known that I, JOSEPH F. SCHAEFER, a citizen of the United States, residing at Cleveland, in the county of Cuyahoga and 5 State of Ohio, have invented a certain new and useful Improvement in Extension-Drawer Construction, of which the following is a full, clear, and exact description.

The object of this invention is to provide 10 a cheap and efficient combination of parts for so supporting a drawer in its cabinet that said drawer may be pulled entirely out of the cabinet and still be suitably supported in a horizontal position; and which will 15 permit the drawer to be entirely separated from the cabinet and replaced therein at will.

The invention consists in the combination 20 of parts shown in the drawing and herein- 20 after described and definitely pointed out in the appended claims.

In the drawing, Figure 1 is a vertical section which shows the cabinet, the drawer, and the means for supporting the latter,— 25 said section being taken in the plane indicated by line A—A on Fig. 2, and when the drawer is closed. Fig. 2 is an inside elevation of one side of the cabinet and the hanger supported thereby, when the latter, 30 is pushed back into the cabinet as far as it can go. Fig. 3 is a sectional side elevation in the plane indicated by the line G—G on Fig. 1, looking in the direction of the adjacent arrow, and with the side of the drawer 35 broken away in places,—said parts being shown in the position they will occupy when the drawer is pulled out as far as it can be pulled. Fig. 4 is an inside elevation of one of the hangers. Fig. 5 is an inside view of 40 one of the hanger supporting strips which is attached to the side of the cabinet. Fig. 6 is a plan view of the rail which is secured to the drawer. Fig. 7 is a vertical sectional view in the plane indicated by line B—B on 45 Fig. 3. Fig. 8 is a vertical sectional view in the plane indicated by line C—C on Fig. 3. Fig. 9 is a vertical sectional view in the plane indicated by line D—D on Fig. 5. Fig. 10 is a vertical sectional view in the plane indicated by line E—E on Fig. 4. Fig. 11 is 50 a vertical sectional view in the plane indicated by line F—F on Fig. 4.

Referring to the parts by reference characters, 1 represents the cabinet which may 55 be constructed to receive one or more draw-

ers. The drawers slide into and out of the open front of the cabinet between side walls 1^a, 1^a, which are parts of the cabinet, and above a floor 1^b which is also a part of the cabinet.

2 represents a drawer of any usual or desired form,—2^a, 2^a representing the vertical sides thereof, and 2^b the bottom thereof.

3, 3 represent the two extension slides or hangers, one being located on each side of 65 the drawer and between a side wall 2^a thereof and the adjacent side wall 1^a of the cabinet. Each hanger is supported upon the adjacent side wall of the cabinet in such manner that it can slide forward and backward horizontally; and each of these 70 hangers supports the adjacent side of the drawer in such manner that the drawer may move horizontally forward and backward, relatively to the hanger, irrespective of the 75 position of the hanger. The means by which the sides of the drawer and the hangers are so slidably supported are the same on both sides of the drawer, wherefore the following descriptions of the means on one side 80 will suffice.

There is attached to the side wall of the cabinet a guide strip 4 which is preferably made of sheet metal. The lower edge of this strip, after it is bent into shape, is continuous from end to end; and the strip is secured to adjacent side wall 1^a of the cabinet by rivets, spot welding or other suitable means, with the lower edge of this guide strip resting on the floor 1^b of the cabinet 90 opening. The lower edge of this strip is bent inward and then upward to form the horizontal flange 4^a, and the upwardly extended flange 4^b, which latter flange is higher at the front end of the strip than it is at 95 the rear end thereof, as is plainly apparent from Fig. 5. The strip 4 is much narrower, up and down, at its rear end than at its front end, as shown in Fig. 5. The upper edge of the narrow rear part of this strip is bent inward to form a horizontal flange 4^c. The wide front part of this strip has its upper edge bent inward and then downward to form a horizontal flange 4^d, and the vertical flange 4^e. Likewise an ear 4^f is bent upward from the rear end of the wide front part of this strip and serves as the means for connecting this part of the strip to the side wall of the cabinet.

The hanger 3, of which Fig. 4 is an inside 110

view, has its lower edge bent inward and upward to form the horizontal flange 3^a and the upwardly exended vertical flange 3^b. At the rear end of the hanger an ear 3^c is bent down in the same plane as that in which the flange 3^b lies. The upper edge of this hanger is bent inward and then downward thereby forming the horizontal flange 3^a and the vertical flange 3^c. A roller 5 is 5 rotatably mounted on a stud 5^a which is rigidly fixed to and projects outwardly from the ear 3^c, and this roller 5 moves in the guideway formed at the rear end of the strip 4 lying between the horizontal flanges 4^a and 4^c and normally resting upon the former, but capable of engaging the latter.

A roller 6 is in the groove formed at the front end of the strip 4 between the body part thereof and the upturned flange 4^b, and 20 is rotatably mounted upon a stud 6^a which extends horizontally between and is fixed to said two parts. The lower edge of the hanger rests and rides upon this roller 6, while the upper edge of the hanger projects 25 behind the flange 4^c at the front edge of said strip.

Several rollers 7 are in the channel which is formed between the body part of the hanger 3 and the upturned flange 3^b thereof, and each of these rollers is rotatably mounted on a stud 7^a which extends horizontally between and is fixed to said two parts.

On the side of the drawer a horizontal rail 8 is fixed by means of rivets, spot welding or the like,—that is to say, the upper edge of this rail is so fixed to the drawer, but the rail below the part so fixed to the drawer, is bent outward and then downward to form the vertical member 8^a which is 35 parallel to but at a slight distance from the side of the drawer. The extreme lower edge of this rail is bent outward to form the narrow flange 8^b whose function is to stiffen the rail. When the drawer is assembled 40 with respect to the hanger, the lower edge of this rail passes over the top edge of the upturned flange 3^b on the hanger, and the lower edge of said rail rests and rides upon the several rollers 7 which are mounted as 45 stated on the hanger.

Near the rear end of the drawer a bracket plate 9 is fixed. This extends outward a short distance from the drawer, and then upward, passing behind the down turned 55 flange 3^c of the hanger,—the upper edge of this bracket lying close to the horizontal flange 3^a of the hanger. When the hanger is pushed back into the cabinet, its rearward movement is limited and stopped by the 60 engagement of the rear end of the down turned flange 3^c with a buffer 10 which is preferably made of rubber and is secured to the inner side of the rear end of the strip 4. When the hanger has been pulled out as far 65 as it can go a buffer 12, preferably made of

rubber, which is fixed to the inner side of the rear end of said hanger, will engage the rear end of the flange 4^d and be stopped. When the drawer has been pushed in as far as it should go, a shoulder, which may be 70 the rear end of the rail 8, which is fixed to the drawer, engages the same buffer 12 and is stopped thereby.

A bell crank lever 14 is pivoted to the inner face of the hanger at the extreme front end thereof, so that the vertical arm of said lever will lie in the path of a stop bracket 15 which is fixed to the outer side of the rail 8 slightly back of the middle of said rail. When, as the drawer is being pulled 80 out this stop bracket 15 hits this down turned arm of the lever 14 the horizontal arm of said lever is engaging the top of the flange 3^d on the hanger, and therefore it is impossible that any pressure from the stop bracket shall swing said lever 14 so as to allow any further forward movement of the drawer. When, however, it is desired to remove the drawer from the cabinet this lever 14 may be swung on its pivot so that the 85 arm thereof which normally hangs down swings rearward and upward. When it has reached a horizontal position, the stop bracket 15 may pass under it, and so permit the removal of the drawer.

When, with the above described construction, the drawer is pulled out, it will usually move relative to the hanger, sliding on the rollers 7 until the stop bracket 15 engages the lever 14. At this time the part of the 100 drawer which is in front of the hanger and is therefore unsupported may overbalance that part of the drawer which is resting on rollers 7 in the hanger. If it does, the front end of the drawer will tip downward very 105 slightly and until the bracket 9 engages the under surface of the flange 3^d of the hanger. By still further pulling out the drawer the hanger is caused to move outward and may continue so to move until the buffer 12 engages the rear end of the flange 4^d. A part 110 of the weight of the hanger and the drawer mounted thereon will be carried by the roller 6, but when the hanger is fully pulled out, the weight in front of this roller will exceed 115 the weight behind it, and the front end of the hanger will tip slightly downward and until the roller 5 at the rear of the hanger engages the flanges 4^c of the strip 4.

Having described my invention, I claim:

1. In a device of the character described, the combination of a cabinet, a drawer therefor and the following parts on each side of the drawer, viz. two horizontal flanges fixed to the side wall of the cabinet lying one over 125 the other and extending forward from a point near the rear of said cabinet, a roller mounted on the cabinet in front of said flanges, a hanger having a straight lower edge which rests and rides on said roller 130

and which has at its rear end a down turned flange, a roller mounted on the outer face of said down turned flange and lying between the said horizontal flanges on the cabinet,—
 5 said hanger having also an inwardly turned horizontal flange along its upper edge, a plurality of rollers mounted on the inner face of the hanger, a horizontal rail fixed to and offset from the side of said drawer and
 10 resting on said rollers, and an offset bracket fixed to the drawer near the rear end thereof and lying beneath said horizontal flange on the hanger.

2. In a device of the character described, 15 the combination of a cabinet, a drawer therefor and the following parts on each side of the drawer, viz. two horizontal flanges fixed to the side walls of the cabinet lying one over the other and extending forward from
 20 a point near the rear of said cabinet, a roller mounted on the cabinet in front of said flanges, a hanger having a straight lower edge which rests and rides on said roller and which has at its rear end a down turned flange, a roller mounted on the outer face of
 25 said down turned flange and lying between the said horizontal flanges on the cabinet,— said hanger having also an inwardly turned horizontal flange along its upper edge, a plurality of rollers mounted on the inner face of the hanger, a horizontal rail fixed to and offset from the side of said drawer and resting on said rollers, an offset bracket fixed to the drawer near the rear end thereof and
 30 lying beneath said horizontal flange on the hanger, a buffer fixed to the cabinet behind and in the path of the down turned flange at the rear end of the hanger, a buffer fixed to the inner face of the hanger near its rear
 35 end, a shoulder fixed to the cabinet in front of and in the path of the last mentioned buffer, a shoulder on the drawer in the path of and in front of said buffer on the hanger, a stop fixed to the side of the drawer,
 40 and a stop on the hanger in front of and in the path of the stop on said drawer.

3. In a device of the character described, 45 the combination of a cabinet, a drawer therefor and the following parts on each side of the drawer, viz. a sheet metal guide strip fixed to the side wall of the cabinet, which strip is narrow at its rear end and wider at its front end, the lower edge of said strip being bent inward to form a horizontal flange and upward to form a vertical flange, and the narrow part of said strip having its upper edge bent inward to form a horizontal flange, and the upper edge of the wide part of said strip being bent inward and then
 50 downward, a roller mounted on the inner face of said strip near the front end thereof, a hanger having horizontal top and bottom edges which are bent inward to form hori-

zontal flanges and then toward each other to form vertical flanges, and said hanger having at its rear end a down turned flange which lies in the plane of the vertical flange along the lower edge of said hanger, a roller mounted on the outer face of said down turned flange and lying between the horizontal flanges at the rear end of said guide strip, and the lower edge of said hanger resting at its front end on the roller mounted at the front end of the guide strip, a plurality of rollers mounted on the inner face of the hanger, an offset horizontal rail fixed to the side of the drawer and resting at its lower edge on said plural rollers, an offset bracket fixed to the side of the drawer and extending beneath the horizontal flange along the top edge of said cabinet.

4. In a device of the character described, the combination of a cabinet, a drawer therefor and the following parts on each side of the drawer, viz. a sheet metal guide strip fixed to the side wall of the cabinet, which strip is narrow at its rear end and wider at its front end, the lower edge of said strip being bent inward to form a horizontal flange and upward to form a vertical flange, and the narrow part of said strip having its upper end bent inward to form a horizontal flange and the upper edge of the wide part of said strip being bent inward and then downward, a roller mounted on the inner face of said strip near the front end thereof, a hanger having horizontal top and bottom edges, which are bent inward to form horizontal flanges and then toward each other to form vertical flanges, and said hanger having at its rear end a down turned flange which lies in the plane of the vertical flange along the lower edge of said hanger, a roller mounted on the outer face of said down turned flange and lying between the horizontal flanges at the rear end of said guide strip, and the lower edge of said hanger resting at its front end on the roller mounted at the front end of the guide strip, a plurality of rollers mounted on the inner face of the hanger, an offset horizontal rail fixed to the side of the drawer and resting at its lower edge on said plural rollers, an offset bracket fixed to the side of the drawer, and extending beneath the horizontal flange along the top edge of said hanger, and stops secured to said guide strip, hanger and drawer for engagement with one another to limit the rearward and forward movement of each relative to the other.

In testimony whereof, I hereunto affix my signature in the presence of two witnesses.

JOSEPH F. SCHAEFER.
